UNITED STATES PATENT OFFICE.

JOHN L. FRUIN, OF NEW YORK, N. Y.

FLUSHING-TANK.

No. 920,126.

Specification of Letters Patent.

Patented May 4, 1909.

Application filed April 25, 1908. Serial No. 429,226.

To all whom it may concern:

Be it known that I, JOHN L. FRUIN, a citizen of the United States of America, and a resident of Brooklyn borough, New York city, and State of New York, have invented certain new and useful Improvements in Flushing-Tanks, of which the following is a specification.

My invention relates to that class of flushing tanks known as a siphon tank, that is, a tank the discharge of which is effected through a siphon outlet pipe so that when the discharge is started the water will continue to flow by siphonic action until the siphon is broken.

The object of my invention is to provide a flushing tank of the siphon type in which the siphonic action is started by the mechanical immersion of a float-valve; the water thus suddenly displaced causing the siphon to fill and the siphonic action to start. My invention, therefore, belongs to the class of what are known as single charge tanks, the entire contents of the tank being practically used at each flushing operation, and the tank being allowed to refill gradually from the water supply pipe.

This invention may be used either as a low-down tank or an over-head tank, with either a top supply or a bottom supply, as preferred. It frequently happens with all tanks used for flushing purposes, whether siphon tanks or not, that the supply fails temporarily owing to the lack of pressure. When this occurs in the ordinary flushing tank the pulling of the chain lets out whatever water is in the tank and then the valve closes. Although the tank fills again by the coming on of the supply, no flushing action takes place until somebody pulls the chain, and therefore if the scant supply of water present when the chain was previously pulled was not sufficient for flushing purposes the article remains unflushed until again called into action.

The object of my invention is to avoid this difficulty and to cause the refilling of the tank by the coming on of the supply to flush automatically, and therefore protection will be afforded against forgetfulness or absence in leaving any articles unflushed because the water supply happens to be stopped at the

time the chain was pulled, inasmuch as the coming on again of the supply immediately causes a full flushing action which effects 55 what the previous lack of flush failed to effect.

The novelty in my invention consists in providing the tank with an adjustable self-locking and self-releasing float-valve, the 60 forcible immersion of which in the waters of the tank will start the siphonic action provided the tank is full. In case the tank is not full enough to have the depression of the float start the siphon the float remains locked 65 in a depressed position until sufficient water enters the tank to start the siphon automatically. In other words, the self-locking and self-releasing secures a full discharge or flush 70 every time it is depressed. The discharge 70 takes place immediately if the tank is full when the float is depressed. It does not start at all if the tank is only partly full, but the float remains depressed so that it cannot be depressed again until sufficient added 75 water enters the tank to start the siphon automatically when the tank is full. The tank then discharges itself and then, but not until then, the float releases itself and assumes a position ready to be lifted by the incoming water until it has returned to its 80 initial position.

My invention consists, therefore, in a flushing tank provided with a siphon outlet and a self-locking and self-releasing float-valve 85 which controls the supply inlet; said float-valve being adapted to lock itself in its depressed position and to unlock itself only when the tank is substantially empty, whereby said tank is siphoned by the depression of 90 the float when the tank is full, and is put into a condition to siphon itself by the depression of the float when the tank is not full.

In the accompanying drawings Figure 1 is a vertical section of my invention applied to 95 an over-head tank fed from the bottom. Fig. 2 is a similar section of my invention as applied to a low-down tank fed from the bottom.

Same letters indicate similar parts in the 100 different drawings.

A is the body of the tank of usual construction provided with a supply pipe *a*, with the usual ball-valve *b*, connected with the float

by the rods *c*, *d*, of any convenient size and location. As an over-head tank the top is open as shown in Fig. 1. As a low-down tank it is usually provided with a cover *B*.

5 C is the siphon which is a piece of plain bent metal, the longer leg of which passes through the bottom of the tank where a tight joint is made by means of the usual jam-nut *e*, and suitable cement or other packing. D 10 is the float pivoted to the tank *A*, at *f*, and normally held in the position shown in the drawings by the water in the tank which, as shown, does not rise to a height sufficient to over-flow the partition *g*, in the siphon, and 15 therefore no siphonic action starts. In this position the ball-valve *b*, is, of course, closed and no more water can enter the tank. The connecting rod *d*, passes through a slotted plate *i*, on top of the float and carries at its 20 upper end an adjusting nut *h*, by means of which the time of closing the ball-valve with regard to the position of the float *D*, may be varied as occasion requires. The depression of the float *D*, and its consequent immersion 25 in the water are brought about by pulling down the chain *E*, as follows: This chain is fastened in the eye *j*, at the outer end of the bent arm *k*, which is hinged to the plate *i*, at *l* at the top of the float. Where the top of 30 the tank is open, as shown in Fig. 1, I provide a guide rod *m*, set in the frame of the tank body and passing through a slot in the bent arm *k*. When the chain is pulled downward the float *D*, moves downward also until the 35 bent arm *k*, reaches the nick *n*, in the guide rod *m*. Slipping into this nick the bent arm becomes locked and therefore the float cannot rise when the chain is released. The arm is unlocked by the weight *p*, rigidly attached to the arm *k*, which causes the slotted arm to turn on the hinge *l*, enough to slip out of the nick *n*, when the tank is so far discharged that the float does not receive sufficient support from the water to hold it up.

40 45 There is then, of course, no danger of the float rising suddenly and the tank continues to empty itself until the siphon breaks by the admission of air at the lower end of the shorter leg. Where the covered tank is used, 50 as shown in Fig. 2, the bent arm *k*, has the nick *n*, and this nick is engaged by the slotted plate *q*, on the under side of the cover *B*, through which said bent arm passes. The 55 unlocking takes place by means of the weight *p*, as just described, causing the arm to swing on the hinge *l*, enough to free the nick *n*, from the slotted plate *q*. The same structure of adjustment, locking and unlocking, would be used if the supply valve were 60 differently situated, the connecting rods being changed accordingly.

The operation of my improved tank as above described is this: Assuming the tank to be full and the float in the position shown

in the drawings, a proper pull on the chain 65 will draw down the float until it locks itself by the catching of the slotted plate or arm and the nick. The water displaced by this depression of the float rises in the siphon above the top of the partition *g*, sufficiently to 70 cause the siphonic action to begin. This siphoning continues until the water of the tank gets so low that it will no longer support the weight of the float and the weight *p*. The weight *p*, therefore tips down the bent 75 arm so as to release the latch. The tank being now empty and the siphon broken, and the inlet valve open, the incoming water will gradually fill the tank and buoy up the float until it lifts the latter into the position originally adjusted for the closing of the inlet valve. In other words, until the tank is full. 80 This adjustment, of course, as before stated, has tipped down sufficiently low to prevent any danger of the siphon starting itself, but 85 sufficiently high to make the depression of the float displace enough water to start the siphon. Assuming the tank not to be full, for lack of sufficient supply, the float will already be partly depressed. A pull on the 90 chain therefore will bring down the float until it locks, but will not start the siphon for lack of sufficient water. There will, therefore, be no flush but there being some water in the tank the float will not unlock itself. 95 The water then coming on through the open inlet will rise and fill the tank without lifting the float and will continue to rise until it overflows the siphon partition when the siphonic action will automatically stop. 100 This siphoning will, of course, continue until it empties the tank enough to cause the float to unlock and then the incoming water will lift the float to its normal position but will not siphon out; the supply being checked by 105 the float closing the inlet valve, until the chain is again pulled.

Among the advantages of my improved flushing tank may be mentioned the very important one that there is no chance for a 110 leaky outlet or flush valve. The great disadvantage of ordinary flush tanks is that it is very difficult to make sure that the flush valve seats itself with a perfectly tight contact after a flushing operation. There are 115 many causes for this. The washer may be worn unevenly. The up-and-down movement of the rod or supporting chain may not be perfectly true. Some particle of grit may work in between the washer and the valve 120 seat. The consequence of this leakage is a constant waste and disagreeable running away of the water which tends to keep the tank insufficiently filled unless the supply is very strong. All this is avoided by my tank 125 through the absence of a flush valve. No water can pass through the outlet pipe until there is sufficient water in the tank to start

the siphon, and when the siphon breaks it remains broken until the tank again fills.

I claim:

A flushing tank provided with an inlet pipe, an outlet siphon, and a self-locking and self-unlocking float whereby the siphon is started and the inlet valve controlled, said

float being adapted to lock itself when depressed and to unlock itself when the water in the tank is practically exhausted.

JOHN L. FRUIN.
